CHARLES A. MINNIE, OF WELLSBURG, WEST VIRGINIA, ASSIGNOR OF TWO-NINTHS TO PETER SELTNER, OF McMECHEN, WEST VIRGINIA, AND TWO-NINTHS TO GEORGE OGDEN, OF WELLSBURG, WEST VIRGINIA.

BATH-FIXTURE.

1,159,324.

Specification of Letters Patent.

Patented Nov. 2, 1915.

Application filed February 17, 1915. Serial No. 8,741.

To all whom it may concern:

Be it known that I, CHARLES A. MINNIE, a citizen of the United States of America, and resident of Wellsburg, county of Brooke, 5 and State of West Virginia, have invented certain new and useful Improvements in Bath-Fixtures, of which the following is a specification.

This invention relates broadly to bath fixtures, and specifically to a shower designed for use in connection with bath-tubs.

The primary object of the invention is to provide a simple and comparatively inexpensive shower device or attachment for 15 bath-tubs designed to be connected to and supplied through the usual combination hot and cold water cock employed in such tubs, and having a shower ring or nozzle which, when occupying its operative position, over- 20 hangs the tub at a substantially central point.

A further object is to provide a device of the character mentioned the shower ring of which normally occupies a lateral out-of-the-way position with respect to the tub and is 25 conveniently adjustable to operative position.

A still further object is to provide a shower attachment wherein the elevation of the shower ring or nozzle may be adjusted to adapt it for use either close to or at a 30 considerable height above the head of the user, as desired.

With these and other objects in view, the invention resides in the features of construction, arrangement of parts and combinations 35 of elements which will hereinafter be fully described, reference being had to the accompanying drawings, forming a part of this specification, in which—

Figure 1 is an elevation of the invention 40 applied to a bath-tub, a portion of the latter being illustrated in broken lines; Fig. 2 is a top plan view of the same, showing the shower ring extended to approximately operative position; Fig. 3 is an enlarged view 45 of a portion of the invention shown in Fig. 1, showing the shower ring in operative position; Fig. 4 is a section on the line 4—4, Fig. 3, looking upward; and Fig. 5 is an enlarged section taken on the line 5—5, Fig. 3.

50 Referring to said drawings, in which like designating characters distinguish like parts throughout the several views—1 indicates a short length of pipe designed to be directed

through the end wall of a bath-tub and to be permanently attached to the combination hot 55 and cold water cock 2 commonly employed for supplying water to such tubs, said pipe being tapped into the body of said cock between the hot and cold water connections 3 and 4 in order that it may be supplied with 60 water of a temperature regulated by manipulation of the individual control valves of said cock. Coupled to the pipe 1 at a point beneath the roll 5 of the tub and extending around and concealed by said roll to a point 65 substantially midway between the ends of the tub is a pipe 6 which connects with a vertically disposed pipe 7 of appropriate length. Attached to the upper end of said pipe 7 is a flexible tube 8 that connects at 70 its opposite end to one end of a suitable conduit which, as herein shown, comprises coupled elbows 9 and 10, said elbow 10 being connected to the horizontally disposed stationary member 11 of a flexible joint 12 75 formed on the end of a pipe 13 which has its opposite end connected to a shower ring 14. Said pipe 13 normally lies suspended in a vertical position, as shown in Fig. 1, the shower ring being thus suspended in an out- 80 of-the-way lateral position with respect to the tub.

When it is desired to dispose the shower ring 14 in its horizontal operative position overlying or overhanging the tub, as shown 85 in Fig. 2, the ring and pipe 13 are swung forward and upward, this movement being permitted by the flexible joint 12, and a curved arm 15 which is mounted on a pivot 16 located at a suitable point, as on the under 90 side of the elbow 10, is then swung around horizontally to an underlying supporting position with respect to the pipe 13, as shown in Figs. 2, 3 and 4.

The elbow 9 or an equivalent portion of the 95 conduit is mounted upon the upper end of a rod 17 which is telescoped within a vertically disposed tubular supporting member 18 so as to permit of vertical adjustment to regulate the height of the shower ring with 100 respect to the tub, as shown in Fig. 3, such adjustment being permitted by the flexible tube 8. A set-screw 19 directed laterally through the tube 18 is adapted for adjustment to impinge on the rod 17 for holding 105 the latter in adjusted position. Said rod has

a longitudinal groove 20 therein in which the point of the set-screw travels when said rod is raised or lowered, said groove and screw coöperating to prevent rotation of the 5 rod which would swing the shower ring from its proper position in relation to the tub.

The tube 18 is rigidly supported by the pipe 7 at a point lateral with respect to the upper end of the latter, as shown in Figs. 10 1 and 3.

A flexible tube 21 having a spray nozzle 22 may, if desired, be attached to the pipe 7, as shown in Figs. 1, 2 and 3, a valve 23 being provided for controlling the flow of 15 water through said tube. As is obvious, however, this spray attachment does not constitute a necessary adjunct. A valve 24 is provided for controlling the flow of water to the shower ring. A valve 25 is provided 20 in the hot and cold water cock 2, the same being designed to be closed when the shower ring 14 or the spray 22 is in use.

It will be apparent that a large spray nozzle or any of various forms of spray or 25 shower attachments may be substituted for the shower ring 14 herein shown. It will also be obvious that the invention is readily applicable to bath tubs not having the roll or flange 5, in which case the pipe 6 may be 30 arranged to occupy any preferred position.

What is claimed is—

1. A shower fixture for bath tubs, comprising an upright pipe disposed laterally of the tub at a point intermediate the ends 35 of the latter and having connection at its lower end with a source of water supply, a supporting member carried by said pipe, a conduit mounted on said member, a tube providing communication between said pipe 40 and one end of said conduit, a second pipe having a flexible joint connection with the opposite end of said conduit, a shower ring carried by said second pipe and normally occupying suspended inoperative position, and pivoted means for supporting said ring in a horizontal position.

2. A shower fixture for bath tubs, comprising an upright pipe disposed laterally of the tub at a point intermediate the ends of 50 the latter and having connection at its lower end with a source of water supply, a supporting member carried by said pipe, a conduit mounted on said member, a tube providing communication between said pipe and one end of said conduit, a second pipe having a flexible joint connection with the opposite end of said conduit, a shower ring carried by said second pipe and normally occupying suspended inoperative position, a 55 pivoted arm carried by said conduit adapted to be moved into supporting relation to said 60

second pipe for holding said ring in operative position.

3. A shower fixture for bath tubs, comprising an upright pipe disposed laterally 65 of the tub at a point intermediate the ends of the latter and having connection at its lower end with a source of water supply, a tubular upright supporting member carried by said pipe, a vertically adjustable rod disposed in telescopic relation to said supporting member, a conduit mounted on said rod, a flexible tube providing communication between said pipe and one end of said conduit, 70 a second pipe having a flexible joint connection with the opposite end of said conduit, a shower ring carried by said second pipe and normally occupying suspended inoperative position, and means for supporting said second pipe in a horizontal position. 75

4. A shower fixture for bath tubs, comprising an upright pipe disposed laterally of the tub at a point intermediate the ends of the latter and having connection at its lower end with a source of water supply, a 85 tubular upright supporting member carried by said pipe, a vertically adjustable rod disposed in telescopic relation to said supporting member, a conduit mounted on said rod, a flexible tube providing communication between said pipe and one end of said conduit, 90 a second pipe having a flexible joint connection with the opposite end of said conduit, a shower ring carried by said second pipe and normally occupying suspended inoperative position, and a pivoted arm adapted to be moved into supporting relation to said second pipe for holding said ring in operative position.

5. A shower fixture for bath tubs, comprising, in combination with a combination hot and cold water cock, an upright pipe disposed laterally of the tub at a point intermediate the ends of the latter and having connection at its lower end with said cock 100 between the valves of the latter, a supporting member carried by said pipe, a conduit mounted on said member, a tube providing communication between said pipe and one end of said conduit, a second pipe having a flexible joint connection with the opposite end of said conduit, a shower ring carried by said second pipe and normally occupying suspended inoperative position, and pivoted means for supporting said ring in a horizontal position. 105

In testimony whereof, I affix my signature in presence of two subscribing witnesses.

CHARLES A. MINNIE.
